UNITED STATES PATENT OFFICE.

GIUSEPPE SIMONETTA AND AUGUSTO ROSA, OF MILAN, ITALY.

AUTOMATIC TELEPHONE SYSTEM.

1,390,729.

Specification of Letters Patent. Patented Sept. 13, 1921.

Application filed March 4, 1918. Serial No. 220,399.

To all whom it may concern:

Be it known that we, GIUSEPPE SIMONETTA and AUGUSTO ROSA, both subjects of the King of Italy, residing at 4 Via Dante, Milan, in 5 the Kingdom of Italy, have invented new and useful Improvements in Automatic Telephone Systems, (for which we have filed application in Italy November 20, 1916, Patent No. 156,926,) of which the following is a 10 specification.

The present invention relates to an improved system of automatic telephony in which the current sent into the line wire by the calling subscriber causes a free trunk line to select, by means of a searcher of the calling line, called hereinafter "line-searcher," one of the contact groups on which the calling line is multiplied and therewith short-circuits a registering device called hereinafter "registrator" and prevents any other trunk line controlled by the same registrator from coming into operation, all this being performed through the calling subscriber taking off his receiver 15 from the hook of the apparatus. The formation of the first figure of the number called up has the following effects: The registrator is set into motion, a selector or trunk line searcher corresponding to the signaled 20 figure is picked out and set into motion, a pointer of the selector is stopped in a determined position corresponding to the calling line, owing to which position the calling line is connected to a free trunk line leading 25 from the hook of the apparatus. The formation of the first figure of the number called up has the following effects: The registrator is set into motion, a selector or trunk line searcher corresponding to the signaled 30 figure is picked out and set into motion, a pointer of the selector is stopped in a determined position corresponding to the calling line, owing to which position the calling line is connected to a free trunk line leading 35 either to a second selector or to a connector according to whether the exchange is adapted to accommodate 10,000 or 1000 lines. The registrator already mentioned is disconnected and a further registrator inserted 40 which is intended either to act upon the eventual second selector in a similar manner to that of the first registrator in respect to the first selector, or to pick out in the connector a point corresponding to the number called up and to connect up the trunk line (which at this moment is served by the registrator in question and is connected to the calling apparatus) with the apparatus called for. The system further comprises 45 a set of magnets for each trunk line of the connector, these magnets being intended to maintain the connection with the line called for if the latter is free, or to break the said connection if the called for line is not free, 50 and the second registrator being liberated 55

and left available for other calls as soon the connection has been established.

The invention also refers to a type of line-searcher differing from those used heretofore in that each rotating pointer of a number rotatable on the searcher spindle corresponds to a trunk line and can be stopped on it and so establish the connection without interfering with the further motion of the searcher spindle and of the other pointers 60 which remain available for other calling subscribers in such a way that two pointers cannot be stopped in correspondence to the same calling line at a time. The new line-searcher accordingly works as many ordinary searchers as the pointers with which it is fitted can comprise a considerable number of subscribers, and yet its construction 65 remains quite simple.

The invention further refers to selectors 70 and connectors, which are mere modifications of the line-searchers in relation to the use for which they are intended and which will be hereinafter disclosed.

Hence a great simplicity in the plant and 75 a great certainty of working is attained.

The invention is illustrated by way of example in the annexed drawings:

Figures 1 and 2 conjointly show the general scheme of the parts described and of 80 their connections.

Figs. 3 and 4 are a vertical section and a plan respectively of a line-searcher.

The line-searcher according to this invention, as represented in Figs. 3 and 4, is 85 adapted for quite a large number of lines and consists of a stationary portion A corresponding to the multiple of the manual system, and of a revolving portion corresponding to the set of plugs in the manual 90 system and consisting of a set of pointers.

The stationary portion comprises a cylinder on whose generating lines are multiplied the subscriber lines in the case of the devices working as calling-line-searchers or as connectors, or the trunk lines from the previous devices in the case of the devices working as selectors. In addition thereto each device comprises a ring-shaped collector provided with contacts C, the auxiliary magnets 100 spoken of hereinbelow being energized across this collector.

The revolving portion comprises a spindle —d— whose rotation is started at the beginning of the call. In this case the spindle 110

- must be provided with a clutch; in the drawing a magnetic clutch is shown consisting of a set of magnets e_0 , in front of which slides a soft iron disk f_0 sufficiently thin 5 to allow of its slightly deflecting under the action of the electro-magnets; the disk f_0 is driven by a motor and revolves continuously; in order to set the spindle d_0 revolving it is obviously sufficient to excite 10 the magnets e_0 . The clutch might however be of any other type whatever, or be dispensed with altogether if the motor can be stopped.

On the spindle d_0 a plurality of pointers g_0 are fitted, the same being suitably spaced across the spindle length and equal in number to the trunk lines that are placed at the disposal of every hundred subscribers. These pointers are loose on the 15 spindle and can be made fast with it by expansions h_0 set at equal angles around the spindle, so that, when running, the pointers are spaced apart by equal angles. In their rotation the pointers pass in front of 20 the polar expansions of a set of electromagnets not shown in the drawing, or they themselves are carrying electromagnets moving in front of a soft iron plate as shown in the drawing. In both cases the pointer can be 25 displaced from its position, its arm g_0 pivoting about the pin l_0 fixed on the spindle sleeve. By this swinging the pointer is released from the expansion h_0 which influenced it and then rests upon the springs 30 facing it and in this way connects a trunk line to the line corresponding to the cylinder generating line in front of which it has been 35 stopped.

The action of the magnets i_0 is determined 40 by a set of brushes m_0 rubbing the contacts of the ring collector.

To each brush there corresponds a pointer and consequently a trunk line. The brushes m_0 are fitted at the outer ends of the 45 radial arms n_0 which are secured to a central hub that partakes of the continuous rotation of the spindle d_0 and are so arranged that when one brush reaches the contact corresponding to a determined 50 trunk line, the corresponding pointer faces that same line.

When a pointer has been brought to a stop and therewith the calling line has been connected through with a free trunk line and 55 with the called for line, no further pointer can be stopped by the same calling line, and the spindle with the remaining pointers corresponding to free lines can revolve on and effect the connection of another calling line 60 with another free trunk line. Besides, the arrangement is such that a pointer can not be attracted unless it be in contact with the expansion h_0 , viz. just in correspondence to its own arm n_0 , the object of this 65 arrangement being to prevent the pointer

being attracted when it is not exactly opposite the cylinder generating line corresponding to the position of its own arm n_0 at that same moment.

The operation of this device is described 70 as applied to the calling-line searcher. The device works just the same when applied to the selectors (or trunks searchers) or to the connectors.

When a subscriber calls up the collector 75 contact corresponding to the line of the calling subscriber is energized, in the manner hereinafter explained. As the spindle rotates the first brush passing over the contact and corresponding to a free line, and therefore 80 rotating its pointer along with it, transmits a current to the stopping magnet i_0 across the said pointer and its expansion h_0 . Accordingly the pointer is tilted and rests upon the springs it faces at that 85 moment, these springs being just those corresponding to the calling line. In this way the pointer makes the connection between the line coming from the calling subscriber and the trunk line corresponding to the 90 pointer.

The selector and connector work in substantially the same manner. Of course the details may be varied from those described and illustrated in the drawing without departing from the spirit and scope of the invention. In particular the spring contacts in the stationary portion might be replaced by rubbing contacts, the pointers being then fitted with brushes that slide over the contacts and swinging on the loose central sleeve only partially. The position and form of the collector, contacts and brush star might also be varied.

By means of the line-searchers, selectors 105 and connectors (these being suitably connected with trunk lines and the latter being fitted with registering devices or registrators that are released automatically as soon as the connection is established) the calling 110 line is connected up to the called one.

In a general way the system is arranged as follows: Each subscriber has at his disposal a device enabling him to break the speaking circuit.

The subscriber lifts his receiver from the hook; by so doing he sets in motion the line-searcher to which his line belongs (one line-searcher takes care of several subscribers, for instance 100, and each subscriber line is 120 multiplied on a generating line thereof) and grounds a fourth wire of his searcher, so that he cannot be called for by other lines. The line-searcher revolves and when a pointer corresponding to a free trunk line 125 reaches the position of the calling line terminal, the pointer is disengaged from its expansion h_0 and stops thus connecting the calling line and the trunk line. Simultaneously the calling line is connected up to a 130

device registering the first figure of the number called up.

The trunk line thus engaged is connected in shunt to all the selectors of the first set 5 in the group to which the calling telephone belongs. The object of the first registrator is to cause the first figure to remain virtually formed a convenient lapse of time and to set the corresponding first selector into 10 rotation, and to stop it as soon as a pointer of the said first selector comes opposite the calling trunk line.

The first pointer coming opposite the calling trunk line, if it is free, comes to a still- 15 stand and connects up the calling trunk line to a secondary trunk line which is connected to a second registrator. The first registrator is at once released and made available for a successive call from a new first trunk line.

20 The second registrator repeats the operation of the first one and so on till the last but one figure of the number of the called line is signaled.

Now the calling subscriber is connected to 25 a last trunk line and to a registrator whose object is to maintain the signaling of the two last figures of the number. When this signaling is completed, the connector belonging to the hundred to which the called up sub- 30 scribe appertains starts revolving. The last trunk lines lead to the connector pointers and, when the revolving pointer connected to the calling line comes opposite the called up line (who is multiplied on the contacts of one of the generating lines of the connector) if the called telephone is free that pointer is brought to a stillstand and connects the caller's line to that of the called subscriber. The registrator is then at once

40 released and the calling signal sent into the called line. When the called up subscriber lifts his receiver from the hook, he is connected up to the calling line across the speaking line. If the called telephone is en- 45 gaged, the pointer is not brought to a still- stand and all parts which had been engaged during the call are now released excepting the set of magnets of the calling subscriber which remain engaged and, while preventing 50 others calling him up, send the "engaged" signal into the calling line.

At the end of the conversation, as soon as one of the users hangs up his receiver, all the parts that were locked during the con- 55 versation are released with the exception of the magnets of the subscriber that has not yet hung up his apparatus, who received a signal, for instance the same "engaged" signal, that advises him of the end of the 60 conversation.

As may be seen, all parts are so arranged that they remain locked only as long as they are working and are set free immediately their action is over.

65 With reference to Figs. 1 and 2, A is the

calling, —B— the called subscriber, —C— the line-searcher, —D— the first registrator, —E— the selector, —G— the connector, —M N— the magnets of the single subscriber-lines for controlling the line-search- 70 ers.

Call.—The calling subscriber lifting his receiver from the hook, disconnects the ringing apparatus, closes the contact 2 and establishes the circuit $T_1-1-2-3-4-a-Batt-75$ T_2 , where and hereinafter Batt— indicates the battery and T— the grounds.

The magnet —a— attracts its armature fitted with multiple contacts and closes the contacts 6—17—9. By closing the contact 80 6 the caller's fourth wire leading to the caller's connector is earthed, and this prevents the caller being called up by others during his conversation. By closing the contact 17 the circuit $T_5-7-16-17-85$ $Rot.-Batt-T_5$ is established and the line-searcher is started; the reference "Rot" associated with an identifying letter, for example, Rot_c , indicates the magnet which controls the rotation of the element with the 90 corresponding capital reference letter, as C, Q, E, and G. By closing the contact 9, the caller's contact 11 in the collector of the line-searcher C is switched in.

Due to the action of the seracher-magnet 95 Rot_c the line-searcher starts revolving and during its rotation a brush corresponding to a free trunk line comes into contact with it, thereby closing the circuit $T_5-8-10-11-12-b-c-13-14-15-T_4$. 100

The magnet —b— is excited and tilts the pointer, thereby causing the latter to switch the trunk line on to the line of the calling subscriber.

The magnet —d— now comes into action 105 and attracts its multiple armature. The circuit being as follows: $T^8-a-d-26-25-22-23-24-b-T^7$; owing to the circuit $T_3-5-10-11-12-b-c-13-14-15-T_4$ the contact 18 is closed and establishes the 110 circuit $T_4-b-24-23-22-21-20-19-18-29-Batt-T_c$, the magnet —b— having been already excited by the circuit from T_3 to T_4 . The contact 18 closes also the circuit $T_5-a-d-26-25-22-21-20-19-18-29-Batt-T_e$ of the third wire. The magnet armature —a— continues to remain attracted and the magnet —d— opens the contact 8, whereby the current no longer passes through 11 and no other pointer can be 120 stopped by the same contact.

The contact 28 is closed and the magnet —c— energized owing to the circuit $T_6-Batt-29-28-c-e-30-31-T_9$; further the magnet —e— comes into action and 125 opens the contact 14, whereby all other trunk lines controlled by the same registrator can not come into action as long as the registrator is working.

The contact 34 is closed and therewith the 130

magnet controlling the registerator is connected to the subscriber's line across the circuit $T_1-1-2-3-36-34-f-Batt-T_{11}$.

Signaling of the first figure.—The above operations being completed by the fact of the calling subscriber lifting his apparatus from the hook, the caller begins to signal the first figure. To this effect the caller, by means of the well known Strowger dial or any similar device, causes a series of interruptions of the contact 2 and the armature of the magnet f , which has been excited by the cited circuit $T_1-1-2-3-36-34-f-Batt-T_{11}$, drops as many times as the interruptions of contact 2 and closes the contact 33 thereby sending as many impulses into the circuit $T_{10}-32-Rot_q-33-Batt-T_{11}$; consequently the magnet Rot_q of the registerator causes the registerator to advance by a step at each impulse; after the first step of the registerator the contact 40 is closed.

Once the signaling of the first figure is completed, the contact 2 remains closed and consequently the armature of the magnet f remains attracted a sufficient time for the delayed-action magnet g coming into operation due to the circuit $T_{13}-40-38-g-39-Batt-T_{12}$, wherewith the contact 41 is closed and the registerator pointers switch in those lines x and y in front of which the pointer has come to stillstand.

The circuit $T_9-31-30-42-41-43-x-Rot_E-Batt-T_{14}$ is established and due to the action of the magnet Rot_E the selector corresponding to the called hundred starts revolving. Also the circuit $T_9-31-30-42-41-43-y-44-h-Batt-T_{15}$ is established and the magnet h of the selector E attracts its armature and closes the selector contact 45. If the trunk line leading to the corresponding selector is free, the circuit $T_{12}-Batt-i-47-48-49\text{ IV}-46-45-50-l-m-51-52-53-Batt-T_{16}$ is established and the magnets $i-l-m$ are energized. The magnet l tilts the pointer and connects the trunk line coming away from the selector to the trunk line leading to the 2nd selector. The magnet m closes the contact 55 and establishes the circuit $T_{18}-l-58-57-56-54-Batt-T_{17}$ and this circuit excites the magnet l . The magnet i closes the contact 59 and establishes the circuit $T_{12}-Batt-59-60\text{ Lib}-T_9$, and the magnet Lib (the magnets Lib being a releasing magnet for registerator D), attracts its armature and due to the circuit $T_4-62-61-60-Lib-59$ keeps it attracted until the registerator's pointer is brought back to its rest position.

On the magnet Lib coming into action the contact 30 is opened and the magnets c and e are deenergized, while the magnet b continues to be energized by

the circuit $T_7-b-24-23-22-21-20-\text{III } 65$ (third wire) $57-56-54-Batt-T_{17}$. Accordingly the registerator D of the first line-searcher is released and left available for a new caller, while the connection of the calling subscriber and first trunk line with the selector still remains subsisting.

Further the magnet m closes the contact 63 and thus establishes the circuit $T_{17}-Batt-63-m-n-64-128-Batt-T_{16}$. The magnet m remains energized although the magnet n opens the contact 51, so that no other line controlled by the same registerator F is stopped until the latter's operation is completed.

The magnet m further closes the contact 73, whereby it connects up with the caller the magnet p , controlling the registerator F, across the circuit $T_1-1-2-3-36-\text{II}-73-p-Batt-T_{20}$. All this is effected owing to the brief pause following the signaling of the first figure.

Signaling of the last two figures.—The caller proceeds to signal the last but one figure viz. the tens figure. The magnet p , which was energized by the last named circuit, drops its armature at each interruption and sends a series of impulses in the circuit $T_{19}-65-69-Rot_r-70-71-72-Batt-T_{20}$ and the tens-pointer in the registerator F advances by a step at each impulse.

When the signaling of the tens is completed the armature of the magnet p remains attracted a sufficient time for the delayed-action magnet q to come into operation and to open the contact 70, whereby the rotation magnet Rot_r of the tens is shut out and the contact 79 closed.

The signaling of the last or unit figure causes the rotation magnet Rot_r ¹¹ to actuate the unit-pointer across the circuit $T_{19}-65-105-Rot_r$ ¹¹-79-71-72-Batt-T₂₀, and the unit-pointer advances by a step at each impulse.

When the signaling of the unit-figure is completed, the armature of the controlling magnet p remains attracted and the contact 74 closed, thus setting into operation the delayed-action magnet r across the circuit $T_{29}-72-74-r-83-T_{21}$. The circuit $T_{29}-81'-Rot_E-T_{29}$, is energized whereby, owing to the action of the rotation magnet Rot_E , the connector G starts revolving and the brushes thereof slide on its collector. When the brush corresponding to the energized trunk line comes opposite the called up subscriber, different cases may present themselves.

The subscriber called up is free.—Under this condition the contact 94 of the connector, to which the fourth subscriber-wire leads, is not earthed since the contact 92 in the corresponding group N is open. When the brush comes opposite the called sub-

scriber, the circuit $T_{22}-s-86-85-F^{111}-F^{11}-84-83-81-82-F^1-F-87-t-88-89-u-90-Batt-T_{20}$ is established across the three winding magnet $-t$.

5 The magnet $-s$ then attracts the pointer of the connector and connects up the line of the called subscriber to the trunk line coming from the selector E.

The magnet $-t$ attracts its armature 10 and closes the contact 96, wherewith the third wire at the called subscriber's as well as at the calling subscriber's end is earthed across the contacts 96 and 97, the magnet A_f being excited by the second wire of the 15 called subscriber across the connection $T_1-1-2-3-36-II-109-A-112-Batt-T_{26}$

The magnet $-u$ closes the contact 123 and energizes the releasing magnets across 20 the circuit—

25 Since the releasing magnets have opened the contacts 64, the magnets $-m$ and $-n$ drop their armatures and the regis- trator F is set free and made available for a new subscriber as soon as it has reached its 30 rest position.

By the closing of contact 96 on magnet $-t$ the circuit $T_{24}-97-96-t-57-III-20-21-25-26-d-a$ T_s is established, on which are branched the circuits $22-23-35-24-b-T_7$ and $57-58-l-T_{18}$, and the magnets $-a-d-b-l$ of the calling subscriber continue to attract their armatures, whereby it is prevented that the called subscriber on lifting his receiver from the hook 40 should start into action the line-searcher to which he is connected. To the said circuit is connected in shunt the magnet $-s$, which accordingly continues to maintain the connection with the called line.

45 The two third-wire windings on the mag- net $-t$ are so designed that when they are in parallel the armature of the magnet $-t$ is attracted, and when they are set in series in the same circuit they oppose one another 50 and the armature drops.

At the called subscriber's end the resis- tance of the ringing apparatus is such that the magnet B_t cannot operate as long as the ringing apparatus is inserted in the circuit.

55 In this condition, the contact 101 being closed, the magnets $-z$ is traversed by an interrupted current and consequently closes the contact 103 at intervals and sends an intermittent current into the ringing appa- 60 ratus of the called subscriber across the circuit: Corr. Alt (alternating current) 103-104-105-Bell-106-107-108-T₂₅.

When the called subscriber unhooks his receiver he thereby closes the circuit T₂₅—

Batt-112-B_t-113-110-99-104-130-65 Microphone 107-108-T₂₅. The magnet B_t is energized and closes the contact 122; the magnet $-t$ is traversed by currents in op- 70 posite directions and lets its armature drop; the third wires are fed across the contacts 121-122— and the speaking line is fed at the caller's end across the earth T₁ and at the called subscriber's end across the earth T₂₅, the speaking connection being thus com- 75 pleted.

End of the conversation; disconnection.—The disconnection is effected when one of the two subscribers hangs up his receiver. The magnet A_t or the magnet B_t are then deéner- gized, the third wires are interrupted, and 80 the magnets $-b-h-s$ actuating the swinging pointers also become deénergized. At the end of the line where the subscriber has hung up his receiver (for instance the called subscriber) also his magnets $-a$ — 85 and $-d$ — are deénergized. At the end of the calling line, where it has not yet been hung up, only the magnet $-a$ — is deéner- gized; the magnet $-d$ — remains excited across the circuit $T_2-5-d-132-131-3-90-2-Micr-1-T_1$, and the "engaged" signal is sent over to the other subscriber. The same applies if the caller has hung up his receiver first.

Called subscriber engaged; disconnec- 95 tion.—If the called up telephone is engaged, the contact 94 of the called subscriber's fourth wire is earthed and the circuit $T_{23}-91-92-93-94-v-95-89-u-90-Batt-100-T_{20}$ is established; the magnet $-v$ — is ener- gized, opens the contact 88 and prevents the magnet $-t$ — from coming into action. Meanwhile the magnet $-u$ — releases the registrator, and the magnets $-m$ — and $-n$ — are deénergized. The third wire is 105 therefore interrupted at the end of the calling subscriber, who receives the "engaged" signal; in the same way as already described also the magnet $-z$ — is deénergized since the contact 101 has been opened.

In a 10,000 subscriber system, in lieu of the connector G a further selector is used which is connected up to the connector by means of a third registrator.

The registrator might also be operated 115 electrically instead of mechanically.

Of course the particulars regarding the form and constructional details can be varied from those described and illustrated without departing from the spirit and scope of the 120 invention.

Having thus described our invention and how the same is to be carried into practice, what we desire to protect by Letters Patent is:

1. In an automatic telephone system, line- 125 searchers adapted to connect the caller's line to a calling line, automatically, upon

the lifting of the receiver hook of the caller's line, registrators associated with the selected trunk and rendered operative by the lifting of said hook, selectors corresponding to the 5 first figure chosen by the trunk line of the registrator, which selectors are actuated by the calling line when the first figure is formed, whereby the calling line is connected to a second free trunk line having a 10 second selector or connector and the first registrator is rendered inoperative and a secondary registrator is inserted, the secondary registrator being thereafter operable to actuate the second selector similarly to the actuation 15 of the first selector by the first registrator or to select in the connector a point corresponding to the called line and to connect the first trunk line that is served by the caller's secondary registrator with the called 20 line, the secondary registrator being set free upon the making of said connection, and a group of magnets for each trunk leading to the connector, said magnets being operable to maintain the connection of the calling line 25 with the called line and to break the connection if the called line is occupied.

2. A searching device for automatic telephone systems comprising a set of springs and contacts arranged on the generating 30 lines of a cylinder, a set of contacts to which each subscriber's line leads, a set of loose pointers arranged at the level of a row of contacts of said set and rendered operative to rotate by expansion elements arranged 35 on a spindle, brushes, equal in number to the pointers, secured to the spindle and bearing on the contacts of the controlling lines, and electro-magnets operative to disengage the expansion elements from the pointers.

40 3. In a telephone system such as recited in claim 1, connection registrators connected to the trunk lines in shunt and to the calling lines successively.

45 4. In a telephone system such as recited in claim 1, magnets effecting the release of the elements recited as soon as either the hook on the calling instrument or the instrument on the called instrument is hung up.

50 5. An automatic telephone system comprising line searchers having the calling lines connected to multiple horizontal circular rows of contacts, a number of pointers revolving in front of said circular rows of contacts and being the extremities of as many trunk lines as the number of the pointers, means to stop the revolution of each pointer independently of the others; regis-

trators associated with the trunk lines and rendered operative when the calling line forms the first figure of the number of the 60 called line, means for starting a first selector when the registrator comes to a standstill and determining on this selector a group for a stop; first selectors of the same construction as the line searchers and having contact springs forming the extremities of a second set of trunk lines arranged in groups, each group comprising the trunk lines corresponding to a determined group of further selectors, the pointers of the first selectors being the 70 extremities of the trunk lines from the line searchers; further selectors with registrators; a final set of registrators to distinctly record the tens and units figures of the 75 called line number; a connector of the same construction as the line searcher, its pointers being the extremities of trunk lines, and the spring contacts on its stationary frame being the extremities of subscribers lines to be called, and having means whereby its 80 registrator establishes for each pointer during its rotation a group where it can stop and ten positions of rest in said group; sets of relays to control the operations, and relays at the connectors to perform the calling 85 of the desired subscriber as soon as the connector's pointer has stopped on the terminal of the called line, to disengage and free the intermediate members as soon as either of the subscribers hangs up the telephone as 90 well as when the revolving connector's pointer finds that the called line is engaged.

6. An automatic telephone system comprising line searchers consisting of several sets of contacts horizontally arranged in circular rows, the rows being vertically superposed so as to form a cylinder, the contacts on the same generatrix being multiplying contacts of a line, a central rotatable spindle, a number of pointers on said spindle, and 95 means for having the pointers driven by the spindle independently, means for disengaging each rotating pointer from the spindle as soon as it connects a calling line, and brushes co-operating with a circular set of 100 contacts and rotating with the spindle.

In testimony whereof we hereunto affix our signatures in the presence of two witnesses.
